UNITED STATES PATENT OFFICE.

DONALD M. SIMONS, OF OSBORNE, PENNSYLVANIA, ASSIGNOR TO STANDARD UNDER-GROUND CABLE COMPANY, OF PITTSBURGH, PENNSYLVANIA, A CORPORATION OF PENNSYLVANIA.

ELECTRODE.

Application filed November 19, 1924. Serial No. 750,740.

My invention relates to the construction of electrodes; it concerns a modification in the shape of an electrode, such as to prevent electrostatic discharge; and it concerns an extension of the surface of the electrode, in immediate association with a body of solid insulation. The structure is such that no spaces can occur, between the surfaces of the conductor and of the body of insulation. Thus sparking and glowing are guarded against. In certain applications for Letters Patent of the United States which already I have filed, I have described specific practical embodiments of the invention which in this application I shall claim in broader aspect. These prior applications are,—an application filed September 18, 1924, Serial No. 738,424, cable joint, and an application filed October 15, 1924, Serial No. 743,645, terminal.

My present invention, embodied as I have said, in my earlier applications, is, for present purposes illustrated in the accompanying drawings, in which Fig. I is a view in medial and longitudinal section, showing diagrammatically the invention embodied in a cable-end, as that cable-end might appear, when subject to test in a laboratory. Fig. II is a diagrammatic view in plan of a sheet of material employed in the building of the structure of Fig. I. Fig. II is positioned relative to Fig. I in such manner as to indicate how assembly is made. Figs. III and IV are views similar to Figs. I and II, respectively, and show the invention embodied in a cable joint.

In Fig. I, I show a cable from which, adjacent its end, the sheath has first been cut away, exposing the envelope 1 of machine-laid insulation, and from which for a less distance the machine-laid insulation too has been cut away, leaving the end 2 of the conductor exposed. Such a cable-end so prepared is ready for certain tests to be performed upon it. It may or may not, for the purpose of these tests, be submerged in oil, as Fig. I of the drawings indicates it to be. The problem which my invention solves is, how to prevent breakdown, from the bared conductor-end, through whatever dielectric

may lie between, to an adjacent body of metal. In Fig. III I similarly show two cable-ends, from which the sheaths have been cut away, exposing the envelopes 1 of machine-laid insulation, and from which the envelopes of insulation have in turn been for less distances cut away, exposing the conductors 2. The conductors are electrically united, as by the sweated-on sleeve of metal 3, and the problem is to prevent electrostatic discharge from the corner of this sleeve over the surface of envelope 1, to the cut-away end of the cable sheath, indicated at 4.

In any electrical installation, bodies on which lines of force terminate when differences of potential exist are properly termed electrodes.

Comparing Figs. I and III, it will be perceived that in both cases there is an electrode (the bared conductor-end 2, Fig. I; the edge of the sleeve 3, Fig. III), electrostatic discharge from which to an adjacent body of conducting material, is to be prevented. Reference to my earlier applications mentioned above will reveal the fact that in them too the same problem is met. In them, however, the electrode to which a protective structure is added, is not the active, current-carrying conductor, nor any part of it, but is the cut-away end of the cable-sheath. It will, however, be manifest from the disclosure of this specification alone, that the invention I am about to describe is applicable to electrodes generally.

Referring first to Fig. I, my invention is achieved by wrapping upon the bared end 2 of the conductor and advantageously, though not necessarily, upon the adjacent stepped end of the envelope of machine-laid insulation, a long web of suitable insulating material, such as paper, which preferably in a single wrap shall form the insulating body 5. This web of paper is provided with a strip of metal, and the strip of metal is so laid and disposed upon the web of paper that, when the paper has been applied, the metal will form the body 6, incorporated with the body 5 of wrapped-on paper. The metal strip which the web of paper carries

extends to that edge of the web, where wrapping begins, or substantially so, and in consequence the body 6 is electrically continuous with the conductor.

- 5 Fig. II shows the web of paper in plan before it is wrapped upon the parts to be protected. In this figure the web of paper is indicated at 9, and the strip of metal which the web of paper carries is indicated at 8. It will be perceived that as the web of paper shown in Fig. II is wrapped upon the otherwise bare cable end of Fig. I, forming around the cable end the envelope 5, the strip of metal 8 will form within the body 6 of insulation the spherical metallic shell 6. This spherical shell will be in electric continuity with the bared conductor end 2 and will constitute electrically an extended, round-surfaced enlargement of the conductor 2. This rounded surface will be incorporated in a body of solid insulation, with no spaces between surfaces of conductor and of insulation where sparking and glowing might occur.
- 25 Considering now the resultant structure, it will be perceived that, electrically regarded, the surface of the conductor has been extended in the surface of the body 6, and that, simultaneously with the extension, the body 6 has been incorporated with a body of solid insulation, in such manner that the meeting of surfaces, as between the body of conductor and the body of insulation, is exact and complete: there is no intervening surface space, where sparking and glowing might occur.

By the particular placement of the strip of metal upon the web of paper, the shape of the enlargement 6 of the conductor is variable and determinable. Fig. I shows the shape to be that of a hollow sphere, surrounding the conductor 2 at its very end. And, manifestly, the spherical surface so produced, embedded as it is in solid insulation, affords a wide and even distribution of strain; this in a structure contained within an intimately enveloping body of insulation, highly resistant to the strains exerted.

50 In making application of the web of paper to the bared conductor 2, a plug of insulation 7, of coiled paper or the like, may be provided as a structural extension of the body of conductor 2, upon which jointly with the bared conductor-end the body 5 may be wrapped.

The whole structure as I have described it, may then be immersed if desired—and ordinarily such will be the desire—in liquid insulation, and the cable may be subjected to test. In such testing, the breakdown strength will be found to have been greatly increased: the danger of breakdown will be practically eliminated.

65 Fig. III illustrates the embodiment of the invention in a cable-joint, where the elec-

trode to be shielded from discharge is the edge of the conducting sleeve 3. In both of my earlier applications mentioned above, the invention is shown in adaptation to the cut-away end of the cable-sheath, for that sheath-end also, as has already been said, is an electrode; here as a sufficient exemplary case, I show it applied to another part of the same joint structure.

Fig. IV shows the web of paper in plan, before it is wrapped upon the parts to be protected. In this figure the web of paper is indicated at 9^a and the strip of metal which the web of paper carries is indicated at 8^a. It will be perceived that as the web of paper shown in Fig. IV is wrapped upon the otherwise bare joint of Fig. III, forming around the joint the envelope 5^a, the strip of metal 8^a will form within the body of insulation the ellipsoidal metallic shell 6^a. This ellipsoidal shell will, as with the shell 6 of Fig. I, be in electric continuity with the bared conductor-ends 2, and the body 6^a will constitute electrically an extended, round-surfaced enlargement of the electrode, such rounded surface being incorporated in a body of solid insulation, with no spaces between surfaces of conductor and of insulation, where sparking and glowing might occur.

The joint of Fig. III will, it will be understood, be completed in suitable manner, as by wrapping on additional paper insulation or its equivalent, bringing to position an all-enclosing joint-casing, making union of the joint-casing at its ends with the cable-sheath, and flushing the joint and filling the otherwise unoccupied spaces within the casing with insulating compound. In Fig. III a joint-casing of familiar form is indicated in dotted lines at 10, in its ultimate position. The practice of the invention in applying to the joined conductors the body 5^a, does not forbid its further use in providing extensions to the cut-away ends 4 of the cable-sheath, as set forth in my earlier applications mentioned above.

Figs. II and IV show the bared ends of the envelope of machine-laid insulation to be stepped, and the web 9^a to be cut to corresponding shape, so that the finished body 5^a shall fit neatly upon the cable-end. That structure is of course electrically considered, very secure and satisfactory. But the showing in that particular is exemplary merely; my invention lies elsewhere; and the shaping of the ends of the bodies 1 of machine-laid insulation and of the ends of body 5^a, whether the two bodies be shaped to make substantial surface to surface contact or not, will be carried out in such particular manner as the engineer may prefer or find adequate. Fig. IV shows the strip 8^a of metal so laid upon the paper web, that when the web is wrapped on to form the body 5^a, the

whole of the body 6^a is contained within and beneath the surface of the body 5^a. It will be manifest that the strip 8^a may if desired extend to the edge last to be applied to the 5 web of paper, and in that case the body 6^a will at its middle come to the surface of body 5^a. Such a formation would give to the body 6^a at its middle its greatest possible cross-sectional diameter; and to its curvature, on this its equatorial plane, the greatest possible radius.

The web will ordinarily be of paper. It may be formed of equivalent material, muslin, for instance, and it will ordinarily be 15 filled with a suitable insulating compound, such as oil or varnish. The body built up of such material is, in its electrical character, a solid body, as distinguished from a body of liquid insulation, which in its very nature 20 is not suited to withstand the strains with which I here am concerned.

The metal strip 8 (8^a) borne by the web of paper or equivalent material may be variously applied; it may be painted on the 25 sheet, or sprayed on, or it may be applied in the form of foil. The sheet may itself be cut to receive the metal in the form of an inlay. The strip of metal may be carried on one side of the web only or on both sides 30 or may form a section of the web, continuous from surface to surface. If it be formed by application to opposite surfaces, the two applications may be made electrically continuous by penetrating holes in the 35 web of paper.

Ordinarily in the wrapping on of the web the successive turns of the strip will make contact turn upon turn, but this is not necessary: an attenuated spiral will have the same 40 effect as a built-up ellipsoid, continuous on every meridian. It is requisite only that the body of metal be sufficient to endure under service conditions.

Preferably, as I have said the body 5 (5^a) 45 is built as a single wrap, in which the spirally laid laminations extend from end to end of the so-built structure.

The proportions given in the drawings are necessarily far from those which actually 50 will obtain, and in this respect the drawings are diagrammatic. The number of turns in building the body 5 (5^a) is in practice vastly greater than the drawings suggest. The web may (particularly in the case of Fig. I) 55 be a hundred feet long, and the convergence of the opposite portions of strip 8, so clearly indicated in Fig. II, will then in the practical embodiment be beyond detection by casual inspection. In such matters the 60 drawings of necessity are not to be taken as literal presentations of the structure.

The particular shape of the body 6 (6^a) developed within the wrapped-on insulation may be varied greatly, merely by varying

the position of the strip. Fig. I shows a 65 globular body, Fig. III shows an elongate, ellipsoidal body, and manifestly the body will in its minute shape be suited to the conditions of service contemplated.

It will be understood, without particular 70 illustration, that the invention is applicable, without any change whatever, to each of the conductors of a multiple-conductor cable, as well as to the single-conductor cable shown.

The wrap is preferably a single web and 75 in making such an installation as that shown in Fig. III, the work may readily be done in the field.

It will be apparent that, while the metal strip is preferably shaped as described above 80 to produce a hollow enlargement of the metallic body, the invention will be present still, even though the enlargement be in effect not hollow, but solid. Such a modification as here is suggested will be accomplished if the sheet of Fig. II be metallized, not along converging lines merely, but over 85 all the interval between these converging lines. And the modification remains still, 90 an embodiment of my invention. In each case the enlargement of the metallic body extends in a surface of revolution with respect to the axis of the body to which the enlargement is made. This term "surface 95 of revolution" which appears in the ensuing claims is, however, a term which applies with mathematical precision in definition when it is a body of circular cross section which is under consideration. In every case the surface so defined is a surface which on 100 every cross section and at all points is equidistant from the original surface of the body to which the enlargement is made, and the phrase "surface of revolution" as I use it 105 will be understood as definite of a surface having that characteristic.

I claim as my invention:

1. In an electrical installation an electrode enveloped in a wrapped-on body of solid insulation, such wrapped-on body carrying, 110 embedded in its structure, a built-up body of conducting material, said body of conducting material being in electrical continuity with the electrode and being disposed in a surface of revolution with respect to the 115 axis of the electrode.

2. In an electrical installation an electrode enveloped in a wrapped-on body of solid insulation within which a metallic extension of the electrode is embedded.

3. In an electrical installation an electrode enveloped in a wrapped-on body of solid insulation of which each convolution extends without break throughout the entire 120 length of the envelope, said body containing and carrying a metallic extension of the electrode.

4. A wrapping for a conductor consisting

of a sheet of insulating material carrying along a line oblique to its length a strip of metal.

5. A wrapping for a conductor consisting of a sheet of insulating material bearing a longitudinally and obliquely extending metal strip, such strip, when the wrapping has been applied, constituting a voltage-limiting surface.

10 6. A wrapping for a conductor consisting

of a sheet of insulating material bearing a plurality of adjacent, longitudinally-extending strips of metal, converging to union, such strips, when the wrapping has been applied, constituting a doubly flaring, limiting 15 surface to voltage stress.

In testimony whereof I have hereunto set my hand.

DONALD M. SIMONS.
